DESIGN FOR AN EMBROIDERED LACE COLLAR OR SIMILAR ARTICLE

Walter Kohn, New York, N. Y.

Application October 23, 1947, Serial No. 142,117

Term of patent 7 years

(Cl. D3—8)

To all whom it may concern:

Be it known that I, Walter Kohn, a citizen of the United States of America, residing in New York, county of New York, and State of New York, have invented a new, original, and ornamental Design for an Embroidered Lace Collar or Similar Article, of which the following is a specification, reference being had to the accompanying drawing, forming part thereof.

The figure on the drawing is a plan view of an embroidered lace collar or similar article, showing my new design.

I claim:

The ornamental design for an embroidered lace collar or similar article, substantially as shown.

WALTER KOHN.
